(57) **CLAIM**

We claim the ornamental design for a mounting bracket, as shown and described.

DESCRIPTION

FIG. 1 is a perspective view of the mounting bracket;

FIG. 2 is a top view thereof;

FIG. 3 is a left side view thereof;

FIG. 4 is a front view thereof;

FIG. 5 is a right side view thereof;

FIG. 6 is a rear view thereof; and,

FIG. 7 is a bottom view thereof

The dashed lines shown in FIGS. 1, 2, 3, 5 & 7 represent portions of the design that form no part of the claim.
